(57) **CLAIM**

We claim the ornamental design for a trigger sprayer shroud, as shown and described.

DESCRIPTION

FIG. 1 is a perspective view of our new design for a trigger sprayer shroud shown in environmental context with a trigger sprayer and bottle.

FIG. 2 is a top view of the trigger sprayer shroud shown in FIG. 1;

FIG. 3 is a bottom view of the trigger sprayer shroud shown in FIG. 1;

FIG. 4 is a perspective view of the trigger sprayer shroud shown in FIG. 1;

FIG. 5 is a rear view of the trigger sprayer shroud shown in FIG. 1;

FIG. 6 is a perspective view of the trigger sprayer shroud shown in FIG. 1;

FIG. 7 is a front view of the trigger sprayer shroud shown in FIG. 1;

FIG. 8 is a side view of the trigger sprayer shroud shown in FIG. 1;

FIG. 9 is a side view of the trigger sprayer shroud shown in FIG. 1; and,

FIG. 10 is an alternate perspective view of the trigger sprayer shroud shown in FIG. 1 shown in environmental context with a trigger sprayer and bottle.

The broken line representations in FIGS. 1 through 10 are for illustrative purposes only and form no part of the claimed design.
